UNITED STATES PATENT OFFICE

EDWARD S. PEAKE, OF WESTERVILLE, OHIO, ASSIGNOR TO THE KILGORE MFG. COMPANY, OF WESTERVILLE, OHIO, A CORPORATION OF OHIO

TOY PISTOL

Application filed September 12, 1930. Serial No. 481,496.

This invention relates to toy pistols of the type known as a "repeater", in which a roll of caps is employed, the caps being automatically fed to the anvil upon each operation of the trigger.

The primary object of the invention is to provide a construction wherein the feeding of the caps will be accomplished without possibility of wrinkling or piling up of the cap strip, such as would prevent the automatic firing of a cap upon each pulling of the trigger.

To this end a cap feeding pawl is employed which is so operated as to insure for each actuation of the trigger the proper movement of the cap strip to place a cap in striking position upon the anvil, where it may be exploded by the hammer.

The invention embodies relatively fewer parts than is customary in constructions of this character and will withstand the hard usage to which such pistols are subjected without fear of breakage.

Referring to the drawing,

Figure 1 is a view partly broken away, showing the parts in normal position.

Figure 2 is a view showing the hammer retracted and the cap pawl engaging the strip.

Figure 3 is a view of the operating mechanism in detail.

In the accompanying drawing, the numeral 10 is applied to the barrel of the pistol and the numeral 11 indicates the anvil or striking plate. The anvil is suitably bowed as shown at 11'.

The numeral 12 is applied to the trigger and the numeral 13 to the hammer, while the numeral 14 indicates an actuator member which is carried upon the trigger and which engages the hammer, all as will be hereinafter described.

The pistol is comprised of two mated castings which are bolted at the points B' and B'', in any suitable manner.

The hammer 13 is provided at its lower end with a notch 15 for a purpose which will be presently described and is pivoted upon a suitable pin 16 formed integral with one of the castings. A leaf spring 17 maintains the hammer normally against the striking plate

and furnishes the force for propelling the hammer to explode a cap, when the hammer is retracted and released.

The trigger 12 is pivoted upon a pin 18, preferably integral with one of the castings 19 and is provided with an extended portion 20 upon one side of which is formed an integral pin 20. The trigger is likewise formed with an integral extension 21 upon one side of which, opposite the pin 20, there is integrally formed a pin 22. The extension 21 is formed with opposed inclined projections 23 and 24 extending laterally upon the opposite side of the extension 21 from the pin 22. A recess 25 is formed in the trigger upon one side of the extension 19 and the extension is provided along the edge of the recess with a suitable projection 26.

The actuating member 14 is pivotally mounted upon the trigger, being provided with a hole 28, which receives the pin 22. Said actuating member has a recess 29, along one edge, and a projection 30 extending over said recess. At one end, the actuating member has a further projection 31, which, as shown, is adapted to engage the recess 15 in the hammer.

The spring 32, shown as a coil spring, has its coil received on the pin 22 with one arm engaging and restrained by the projection 29 and the other arm restrained by and engaging the projection 26. In this manner, the actuating member 14 is always spring projected away from the trigger.

The spring 33 is a similar type of coil spring having its longer arm engaging under the projection 23 and restrained thereby and its shorter arm engaging a pivoted cap pawl 34, which will now be described.

The said cap pawl 34 is provided with a hole 35, which receives the pin 20. This pawl is preferably formed of sheet metal and at one end is provided with a right angled extension 36. One edge of the pawl 37 is cut away to provide a tang 38, which, with the wall from which it is struck, forms a suitable guide for one end of the coil spring 33. It will be understood that the tang 38 is bent to form a substantially right angled lateral projection and that the spring is received be-

tween the wall of the pawl and the parallel portion of the tang. The lateral extension 36 which is bent at right angles to the body of the pawl forms the contact portion of the pawl with a strip of caps, indicated at 39. The roll of caps is indicated at 40 and is mounted upon a suitable pin 41, integral with one of the castings.

The spring 33 is a compression spring and will, therefore, at all times, act to draw the pawl toward the trigger and hence toward the anvil over which the cap strip passes.

It will be seen that the pawl in normal position, referring to Figure 1, is limited in its movement by the projection 24, the said pawl engaging on one side of such projection.

When the trigger is pulled, the extension 19 is raised in this manner, raising the pawl 34 which, by reason of the spring 33, is forced toward the cap strip with its contact edge 36 engaging the cap strip, so that as the extension 19 continues to rise, the pawl 34 will push the cap strip upwardly to bring a cap into striking position. At the same time, the actuator member 14, which, as stated, is normally spring projected and has its projection 31 engaging in the notch 15 of the hammer, will be drawn forward, so that the projection 31 will act to retract the hammer, as shown in Figure 2 and the parts are so co-related that when the trigger has reached the limit of its movement, the projection 31 will ride out of the recess in the hammer to permit the spring 17 to force the hammer to strike and by this time a cap is in the proper striking position. Upon release of the hammer and its explosion of the cap, the hammer will be in normal position, while the spring 32 will force the trigger to return and the projection 40 31 will ride into the recess of the relatively fixed hammer. The movement of the trigger, by reason of the action of the spring 32, will force the pawl member away from the cap strip and downwardly with the trigger as the trigger assumes normal position and whence the spring 33 will draw the pawl toward the hammer and into engagement with the stop 24.

By this construction, the parts are so timed that by no possibility can jamming occur such as would result if the cap strip were permitted to wrinkle or pile up. This is overcome, as stated, by having the contact portion 36 of the pawl spring pressed at all times toward the trigger and anvil, so that movement of the trigger will force the pawl, as it rides up, to contact with the anvil and a continued further movement of the trigger will result in the proper upward movement of the cap strip the required distance. The pawl is held in engagement with the cap strip as long as the trigger is retracted, but as soon as the hammer is released to strike, the pawl is automatically disengaged and rides free

of the cap strip, so that there is no opportunity for wrinkling.

I claim:

1. A pistol of the class described comprising a trigger, a hammer, means carried by the trigger for actuating said hammer, a cap strip feed plate, and means normally pressed toward the trigger and carried thereby for engaging and moving a cap strip over said feed plate when the trigger is retracted, said means comprising a pawl having a longitudinal edge and a compression spring having legs, one extending substantially parallel with the longitudinal edge of said pawl and engaging the same near its free end and the other engaging the trigger.

2. A pistol comprising a trigger, a hammer, means carried by the trigger for actuating said hammer, a cap strip feed plate, and means normally pressed toward the trigger and carried thereby for engaging and moving a cap strip over said feed plate when the trigger is retracted, said means comprising a pawl formed of a flat metal strip having a longitudinal edge cut away near its free end to provide a tang, and a spring having arms, one engaging the trigger and another arm extending longitudinally of said pawl and engaging said tang.

3. A pistol of the class described comprising a trigger, a hammer, means carried by the trigger for actuating the hammer, a cap strip feed plate, a pawl pivotally carried by the trigger for engaging and moving a cap strip over said feed plate, said pawl comprising a flat metal strip having a longitudinal edge cut away near its free end to provide a tang, and a spring mounted on the trigger and having arms, one engaging the trigger and another arm extending longitudinally of said pawl and engaging said tang.

In testimony whereof I have hereunto set my hand.
